UNITED STATES PATENT OFFICE

WILFRED R. BENDY, OF CHICAGO, ILLINOIS

COOLING CHAMBER

Application filed July 19, 1927. Serial No. 207,007.

My invention relates to improvements in cooling chambers especially adapted for use in cement factories for cooling hot Portland cement clinker as it leaves the kiln, the main object of the invention being the provision of a simple and efficient construction of this character.

Another object of the invention is the provision of an attachment for existing cooling cylinders for increasing their cooling capacity.

Another object of the invention is the provision of a construction whereby the capacity of a cooler of this character may be greatly increased and thereby the size of a cooler of a given capacity may be greatly reduced.

Another object of the invention is the provision of means whereby air entering the cooling chamber is heated as it enters the same.

Another object of the invention is to provide means whereby the cooling of cement clinker occurs partially outside of the cooling chamber, thereby relieving said chamber of the necessity of withstanding the heat thus removed.

Another object of the invention is the provision of a cooler, as above indicated, operating without moving parts or machinery.

Another object of the invention is to lift, drop and scatter the clinker inside of the cooler through the major portion of the revolution of each lifting element, thereby prolonging and distributing the cooling action and greatly aiding the same.

Another object of the invention is the provision of means whereby air admitted to the cooler is compelled to pass in intimate contact with the hot material.

Another object of the invention is to provide means whereby the material may be lifted and scattered at a point in the cooler where the heat ordinarily prevents the use of the usual steel lifter bars and shelves.

Another object of the invention is to provide means for admitting the air as outlined above at the same time preventing the egress of the material treated.

Another object of the invention is to provide a construction and arrangement by means of which each supplemental individual

cooling element is itself cooled individually to prevent overheating thereof.

In general the objects of the invention are attained by providing pockets applied to the periphery of the upper portion of an ordinary revolving cooling chamber, said pockets being adapted and arranged to receive the heated material, thereby exposing it to the cooling action of an external atmosphere, then lifting said material and gradually discharging it through gravity into said cooling chamber, thereby prolonging the time during which said material is exposed to the outside atmosphere and also prolonging the time during which said material is permitted to fall through the cooling draft of air in the cooling chamber.

The pockets are so designed and arranged as to admit air to the cooling chamber, said air thereby cooling the material and the pockets and also being itself heated as it enters the cooling chamber.

The invention consists in the combinations and arrangements of parts hereinafter described and claimed.

The invention will be best understood by reference to the accompanying drawings forming a part of this specification and in which—

Fig. 1 is a side view, shown partially in section, of a cooling chamber embodying the invention;

Fig. 2 an enlarged transverse section taken substantially on line 2—2 of Fig. 1; and

Fig. 3 a sectional perspective view of one of the cooling pockets detached.

The preferred form of construction, as illustrated in the drawings, comprises a revolving cooling chamber set, as indicated, at a slight inclination to the horizontal and divided into an upper portion 10 and a lower portion 11, as indicated. The cooling chamber 10 and 11 is made of an outer metallic shell, as indicated, and is provided near each end with bearing rings or collars 12 mounted upon grooved rollers 13 upon suitable abutments 14, said rollers and abutments being set to support said cooling chamber in inclined position and permit of free revolution thereof.

The cooling chamber is provided centrally with an annular gear 15 meshing with a pinion 16 on a drive shaft 17 and by means of which the cooling chamber is slowly rotated. At its upper end the cooling chamber projects, as shown, into a chamber 18 in and through which the hot cement clinker is fed into the upper end of the cooling chamber in the usual way. The lower end of the cooling chamber is arranged over and 10 discharges into a discharge hopper 19, and the usual lining 20 of refractory material, such as fire brick, is provided for the upper portion 10 of the cooling chamber. The 15 lower portion 11 of the chamber is also provided with the usual lifting or scattering bars 21.

So much of the cooling chamber as has already been described is the usual arrangement for the purpose, operating in the usual way in cement factories for cooling the hot clinker from the kilns and constitutes no part of my present invention except in so far as the same co-operates with the parts 25 to be presently described.

Arranged in the periphery of the upper portion 10 of the cooling chamber, is a plurality of radial openings 22, each opening being lined and protected by a heavy casting 23 having an outer securing flange 24 resting against the outer shell of the chamber. A cooling pocket 25 is arranged on the periphery of the chamber part 10 over each of the openings 22, as shown. Each 30 of the said pockets 25 consists of a heavy casting in the form indicated, with an opening 26 at its inner end registering with the corresponding opening 22. Each pocket is provided with a perforated securing flange 35 27 lying over the corresponding flange 24, and common bolts are employed as shown for securing said flanges in place.

The cooling chamber is caused to rotate in the direction of the arrow in Fig. 2 and with 40 reference to such direction of rotation the forward side of each cooling pocket is arranged to extend radially, as shown from the periphery of the cooling chamber. The rear side of each pocket is provided with a 45 rearwardly extending recess 28 having an abrupt inner shoulder 29 and an inclined outer shoulder 30. Each pocket is also provided at its outer end with an open goose-neck trap arranged as shown with a passage 31 extending forwardly from the outer end of the pocket and then curving inwardly and rearwardly at 32 to form a trap which will admit air to the outer end of 50 each pocket, but will prevent egress of the material being treated, as shown.

In operation the material to be treated, such as the hot clinker from a cement kiln, is fed in the usual way into the upper end 55 of the cooling chamber 10 and progresses

slowly therethrough as said chamber revolves in the usual way, being discharged in cooled condition into the discharge hopper 19.

As will be noted from Fig. 2 of the drawings, during the revolution, the pockets will receive material as they pass across the bottom of the chamber, elevate said material and gradually discharge the same as they revolve, the lateral recess 28 of each pocket retaining said material for the major portion of the revolution, as indicated, and thus gradually discharging and distributing the material throughout the revolution. It will also be noted that air will be admitted to the outer end of each pocket, said air thus passing in intimate contact with the material in the pockets serving to cool both the pockets and the material and also itself being heated prior to introduction into the cooling chamber and the kiln proper. The construction set forth will be found to be a simple and efficient one for the purpose attaining the objects outlined above in a simple and efficient manner and without use of moving parts or machinery.

While I have illustrated and described the preferred form of construction for carrying my invention into effect this is capable of variation and modification without departing from the spirit of the invention. I, therefore, do not wish to be limited to the precise details disclosed but desire to avail myself of such variations and modifications as fall within the scope of the appended claims.

I claim:

1. A construction of the class described comprising a revolving chamber; and one or more material receiving pockets exposed to the outside air on all sides projecting outwardly from and opening through the periphery thereof and adapted and arranged to receive material from said chamber at a low point and elevate and discharge said material into said chamber to effect a cooling of said material.

2. A construction of the class described comprising a revolving chamber; one or more material receiving pockets exposed to the outside air on all sides projecting outwardly from and opening through the periphery thereof and adapted and arranged to receive material from said chamber at a low point and elevate and discharge said material into said chamber; and means for admitting air to said pockets but preventing flow of solid material therefrom to effect a cooling of said material.

3. A construction of the class described comprising a revolving chamber; one or more material receiving pockets exposed to the outside air on all sides projecting outwardly from and opening through the per-

riphery thereof and adapted and arranged to receive material from said chamber at a low point and elevate and discharge said material into said chamber; and an open trap 5 for admitting air to said pockets but preventing flow of solid material therefrom to effect a cooling of said material.

4. A construction of the class described comprising a revolving chamber; one or 10 more material receiving pockets exposed to the outside air on all sides projecting outwardly from and opening through the periphery thereof and adapted and arranged to receive material from said chamber at a low 15 point and elevate and discharge said material into said chamber; and a goose-neck open trap for admitting air to said pockets but preventing flow of solid material therefrom to effect cooling thereof.

5. A construction of the class described comprising a revolving chamber: one or more material receiving pockets projecting outwardly from and opening through the periphery thereof and adapted and arranged to 25 receive material from said chamber at a low point and elevate and discharge said material into said chamber; and a goose-neck open trap having an air passage extending from the outer end of each pocket first for- 30 wardly and then curving inwardly and rearwardly therefrom for admitting air to said pockets but preventing flow of solid material therefrom to effect a cooling of said material.

6. A construction of the class described comprising a revolving chamber; one or more material receiving pockets projecting outwardly from and opening through the periphery thereof and adapted and arranged 40 to receive material from said chamber at a low point and elevate and discharge said material into said chamber; and a goose-neck open trap having an air passage extending from the outer end of each pocket first for- 45 wardly and then curving inwardly and rearwardly therefrom for admitting air to said pockets but preventing flow of solid material therefrom, there being also a lateral extension on the rear side of each pocket adapted 50 to receive and carry material during the major portion of the revolution of each pocket to effect a cooling of said material.

7. A construction of the class described comprising a revolving chamber set at an 55 inclination to the horizontal and consisting of an upper and a lower part; a lining of refractory material for the upper part of said chamber; lifting and agitating bars on the inner periphery of the lower portion of said 60 chamber; one or more material receiving pockets projecting outwardly from and opening through the periphery of the upper portion of said chamber and adapted and arranged to receive material from said chamber 65 at a low point and elevate and discharge

said material into said chamber; and a goose-neck open trap having an air passage extending from the outer end of each pocket first forwardly and then curving inwardly and rearwardly therefrom, the forward wall of each 70 pocket extending substantially radially and the rear wall of each pocket being provided with a rearwardly extending recess having an abrupt shoulder at its inner end and an inclined shoulder at its outer end leading 75 gently and gradually to the corresponding goose-neck trap to effect a cooling of said material.

8. A construction of the class described comprising a revolving chamber having a refractory lining, one or more material receiving pockets exposed to the outside air on all sides projecting outwardly from and opening through the periphery thereof and adapted and arranged to receive material 80 from said chamber at a low point and elevate and discharge said material into said chamber to effect a cooling of said material.

In testimony whereof I affix my signature at 10 South LaSalle Street, Chicago, Illinois.
